CLAIM

The design for a muzzle for a sheep or cow, as shown and described.

DESCRIPTION

FIG. 1 is a perspective view of a muzzle for a sheep or cow showing my new design;

FIG. 2 is a top plan view thereof;

FIG. 3 is a right side elevational view thereof;

FIG. 4 is a front elevational view thereof; and

FIG. 5 is a rear elevational view thereof.

The fragmentary broken line representation of an animal in FIG. 1 is for illustrative purposes only and forms no part of the claimed design.

FIG. 1.

FIG. 2.

FIG. 3

FIG. 4.

FIG. 5
